UNITED STATES PATENT OFFICE.

JESSE A. B. SMITH, OF STAMFORD, CONNECTICUT, ASSIGNEE TO UNDERWOOD TYPE-WRITER COMPANY, OF NEW YORK, N. Y., A CORPORATION OF DELAWARE.

TYPE-WRITING MACHINE.

1,290,387.

Specification of Letters Patent.

Patented Jan. 7, 1919.

Application filed April 28, 1917. Serial No. 165,055.

To all whom it may concern:

Be it known that I, JESSE A. B. SMITH, a citizen of the United States, residing in Stamford, in the county of Fairfield and State of Connecticut, have invented certain new and useful Improvements in Type-Writing Machines, of which the following is a specification.

This invention relates to typewriting machines, especially to machines which are intended to be used for writing on webs of paper, and have a revoluble platen and a traveling carriage.

The invention is herein disclosed as applying to an Underwood typewriting machine, modified somewhat along the lines of the patent to Wernery & Smith, 1,132,055. The machines disclosed in said patent are capable of writing upon what is known as a fan-fold web, which is so folded as to make several thicknesses of work-sheets which afterward can be separated.

Such a fan-fold web has the great advantage that headings, etc., printed thereon are positively held in alinement with each other upon the several plies even when feeding around the platen, because each web is bound to the two adjacent webs by the integral edges at the fold, and these prevent either ply of the fan-fold sheet from feeding faster than the others.

The present invention includes devices which are adapted to retain many of the advantages of said patent, and at the same time enable separate webs or plies to be used with facility, thus permitting one web to be of one color or quality of paper, while the other webs may be of different qualities or colors.

In the form of the invention herein disclosed, the carriage of the typewriter is in many respects like that in the patent referred to, and includes a carbon paper carriage which is adapted to be moved forwardly and backwardly along the usual typewriter carriage. The webs of paper, owing to their weight, are usually mounted upon stationary supports, so that the typewriter carriage is relieved of the strain of driving them. The rolls, which deliver the webs to the typewriter carriage, are according to the present improvements placed so that before reaching the typewriter carriage, the webs are free of tension or are unsupported for quite a distance, thus allowing the

typewriter carriage to travel almost unimpeded by the webs, because the space over which the webs are free of tension enables the webs to twist freely and idly in that space. Instead of being actually unsupported, the webs may lie for a part or all of the distance upon a flat table, which permits them to slide or swerve sidewise at will.

Owing to the fact that the paper forming the webs has some thickness, and that this thickness at the platen is materially increased by interleaved carbon papers, the outside web normally would tend to travel considerably faster around the platen than the inside web, with the result that if the forms printed on the different webs register when the leading edges of the webs are first inserted into the typewriter, they very soon cease to register because the outside web travels faster than the inside web.

The present invention is adapted to overcome this difficulty, by causing the webs to be positively united to each other while the platen is being used for writing. This may be effected by putting a clamp on the carbon paper carriage of the patent aforesaid, said clamp being adapted to positively grip the webs together during the forward feeding of the webs in the act of feeding, but capable of being released by the typist when the carbon paper carriage is pushed rearwardly.

The invention may also include a connection to the carbon paper carriage, such that when pushed rearwardly, the carriage will unwind practically the full length of a form from the webs, so that the subsequent line-spacing operation in filling out the forms, will not throw upon the line-space lever the load of unwinding the webs. This also has the advantage of producing some slack in the webs which serves to diminish the side twisting of the webs which ensues from the travel of the typewriter carriage.

It is convenient to connect the clamp on the carbon paper carriage, which positively holds the webs with an analogous clamp which is adapted to seize the webs and unwind them from their rolls, thus simplifying the structure and at the same time co-ordinating the parts, so that the advantageous slack is produced at the proper time.

Certain features herein disclosed are covered by divisional application No. 242,734, filed July 1, 1918; but the claims herein are

limited to combinations not disclosed in said divisional application.

Other features and advantages will hereinafter appear.

5 In the accompanying drawings,

Figure 1 is a perspective view, largely broken away, showing the invention as applied to the machine of the aforesaid patent.

10 Fig. 2 is a sectional side view of the same, with the parts set for beginning to fill out a fresh form.

15 Fig. 3 is a sectional side view, showing the webs stretched out straight, and the carbon paper carriage clamp released, just at the moment of starting to push the carbon paper rearwardly, preparatory to bringing a new form to the printing point.

20 Fig. 4 is a view similar to Fig. 3, but shows the carbon paper carriage clamp released at the end of its rearward movement.

25 In the Underwood typewriting machine, types 1 at the outer ends of type-bars 2 strike against the front side of a rotatable platen 3 in a carriage 4. The platen 3 is rotated by means of a knob 5, mounted on a stub axle 6, or by the line-space lever 7, which is adapted to drive rearwardly a slide 8 effective on the line-space detent wheel 9. The platen is mounted in a swing frame 10, which is journaled on a front axle 11, in such a way, that as the swing frame 10 is thrown upwardly and forwardly, the platen swings therewith, but is constantly kept engaged with the line-space mechanism because a pinion 12 fast 35 to the end of the platen axle, remains in mesh with a pinion 13 fast on the shaft 11, and the pinion 13 is also in mesh with a pinion 14 fast to the stub axle 6. When the swing frame 10 is swung up, the platen occupies the position seen in Fig. 3, in which position webs 15, 16 and 17 may be drawn practically straight from the rear of the machine under the platen to have their leading ends gaged by an adjustable outer end gage 18.

40 45 After being thus drawn forward and gaged by abutting them against the bottom of said gage 18, the webs are usually cut off. This is done after the platen 3 is swung back to its normal position, there being provided 50 for this purpose a knife 19, adjacent the front of the machine. The usual front and rear feed rolls 20 and 21 hold the webs 15, 16 and 17 against the platen, during the severing operation while the platen is latched in 55 its downward normal position by the usual latch 22, which is swung forward by a spring 23, so that it catches over a pin 24 on the handle 25, which is provided for swinging the swing frame 10 upward and forward.

60 65 As the webs 15, 16 and 17 are fed forward for the purpose of writing on them, they draw with them interleaved carbon sheets 26 and 27, which are clipped to the usual cross-bars 28 projecting from the opposite sides of a carbon carriage 29, common in this type

of machine. The carbon paper carriage 29 runs on rolls 30, which roll on rails 31 fast to the typewriter carriage, said rails being united by a cross-bar 32 at their rear ends, thus forming a frame which includes a wheel 33, traveling on a rear rail 34. At the front end the rails are fast to brackets 35 on the typewriter carriage adjacent the usual rear carriage rail 36. When the webs 15, 16 and 17 are stretched out flat in the manner shown 70 in Fig. 3, the carbon paper carriage 29 is usually pushed rearwardly by a handle 37, so as to shift the carbon paper sheets 26 and 27 back to the position seen in Fig. 4, in which position, the carbon paper sheets 80 are clear of the knife 19, with the result that the carbon paper sheets remain intact while the webs are being later torn off.

85 In order to properly align the webs, there are provided on the swing frame 10 adjustable edge gages 38, formed as the turned-up edges of plates 39, which lie on the table 40. Besides the edge gages 38, there are also provided edge gages 41 adjustably mounted on the carbon paper carriage 29, these latter 90 edge gages serving to guide the webs straight as they approach the platen 3.

95 The webs as herein shown are drawn from three spools 42, 43 and 44, which are journaled on spindles in a suitable fixed frame 45. As herein illustrated, these spools are beneath the typewriting machine and may be conveniently placed near the floor, under whatever table the typewriting machine is mounted on for the time being. From the 100 spools 42, 43 and 44, the webs are led past guides 46 from which they extend in a straight clear reach to a second set of guide 47. The reach from 46 to 47 may be equal to or greater than the travel of the carbon 105 paper carriage 29, for reasons which will presently appear.

110 From the guides 47, the webs rise and turn forwardly over the rod or bar 32, which, therefore, may if desired be several feet vertically from the guide 47, thus making any twisting of the webs, between 47 and 32, (due to travel of the type-writer carriage) of negligible effect on the webs from the rod 32 forward to the platen 3.

115 In order to cause the webs 15, 16 and 17 to maintain successive forms printed on each web in register with those on the other webs, the webs are positively clamped together, preferably by pressing them down upon the 120 carbon-paper carriage 29, with the result of counteracting the tendency of the outside web to feed around the platen faster than the inner one. There is provided on the carbon paper carriage a clamp 48 adjacent each side of the web, to positively grip the plies. For this purpose the clamp may include two members or jaws 49 and 50. The member or jaw 49 may be mounted on a rock arm 51 fast to a shaft 52, said shaft also carrying a 125 130

second rock arm 53, which carries a pin 54, riding in an arcuate cam opening 55 in a plate or member in the form of a segment 56, so that swinging the segment forward, 5 cams the pin 54 down, thus locking the clamp. This segment 56 is adapted to be rotated by the finger of the typist by means of a finger-piece 57 which controls said segment and therefore the clamps 48. The finger-piece 57 is adjacent the handle 37 and pivoted thereon at 58, so that the hand of the typist in adjusting the carbon paper by the handle 37, is enabled to readily adjust the finger-piece 57 by a motion of a finger 10 at the same time. The connections between the finger-piece 57 and the cam plate 56 include a rearwardly extending link 59, pivoted to the finger-piece 57 at its forward end, and pivoted at its rear end to a rock arm 60, 15 forming part of bell crank 62, fast on a shaft 61, to which shaft said segment 56 is likewise fast. When the handle 37 is pushed to move the carbon sheets 26 and 27 rearwardly, the typist pulls the finger-piece 57 forwardly on the handle 37, thus freeing the clamp 48. This swings upward an arm of bell-crank 62, permitting a latch 64 to be drawn by a spring 65 under the rear arm 66 of the bell crank, thus latching the finger-piece in its forward position, and therefore holding the clamp 48 unlocked.

The typist then pushes the carbon paper carriage 29 rearwardly to the position seen in Figs. 2 and 4, thus drawing the carbon sheets 26 and 27 to a point behind the knife 19. At this time a tail 67 of the latch 64 projecting downwardly below the pivot 68 thereof, strikes against a stop 69 fast on the left-hand rail 31, thus causing the latch 64 40 to free itself from the bell crank 62, thereby permitting a spring 70 coiled around the shaft 61 to swing said shaft to cause the clamps 48 to become effective to bind the webs together. The stop 69 arrests the carbon paper carriage 29, and may be adjustably fastened at any point on its rail 31 to suit the work in hand. For this purpose it is held to said rail by a thumb-screw 71.

When the clamp 48 is engaged, as shown 50 in Figs. 2 and 4, the webs 15, 16 and 17 positively grip each other, with the result that the headings printed on the webs 15, 16 and 17 will accurately maintain register each with the others.

55 In connection with the rolls 42, 43, 44, there is provided a web-advancing clamp 72, as part of a lower carriage 73, which is provided with rolls 74 to run on rails 75 extending rearwardly from the support 45. 60 The clamp 72 may include jaws 76 and 77 like the clamp 48, and the clamp 72 is preferably in duplicate, so that there is such a clamp 72 near each margin of the webs 15, 16 and 17. To operate these clamps together, they are mounted on a transverse

shaft 78, which is provided with a rock arm 79 having a pin 80 working in a cam slot 81 in a plate 82. This plate is preferably connected to be operated in conjunction with the cam plate 56, and for this purpose may 70 be connected to the finger-piece 57 by means of a horizontal link 83 extending from a lower extension 84 of said finger-piece, said link 83 operating a rock arm 85 fast to the end of the shaft 86 at one side of the 75 typewriter carriage. This rock arm operates the cam plate 82 by means of the rock shaft 86, said rock shaft having also fast thereto a second rock arm 87, which is joined by a link 88 to a rock arm 89 splined to a 80 shaft 90 adjacent the shaft 94. The shaft 90 is journaled on brackets 91 forming part of the carriage 73, and operates the cam plate 82 by means of arms 92 and 93 on the shafts 90 and 94 respectively, said arms being joined by a link 95.

Since the cam plate 82 is fast on the shaft 94, it will be seen that the finger-piece 57 may operate the segment cam plate 82 and 56 in unison, in such a way that one is 90 always effective. The carriage 73 has been described as running on fixed rails 75, while the carbon paper carriage 29 runs on the rails 31, which form part of the typewriter carriage. In order to enable the link 88, 95 which connects the clamps 48 and 72, to remain vertical despite the feeding of the typewriter carriage sidewise past the lower carriage 73, the splined arm 89 is slidden along its shaft 90 by means of a stiff vertical bar 96 projecting downward from the carbon paper carriage and having at its lower end a fork 97 which embraces the rock arm 89, thus causing said rock arm to slide 100 along its shaft with the travel of the typewriter carriage. 105

When the carbon-paper carriage is pushed back with the clamp 48 released and therefore ineffective, the clamp 72 will be seizing the lower reaches of the webs 15, 16 and 17 between the supports 46 and 47, thus 110 unwinding each web 15, 16 and 17 from its spools 42, 43 and 44 an amount precisely equal to the amount that the carbon carriage is pushed backward. This produces a bight 98 in the webs between the support 47 and the rod 32. When the carbon-paper carriage is pushed all the way back, the stop 69 causes the clamp 48 to seize and the clamp 72 to release. Since the clamp 72 is released, 115 it follows that during the subsequent forward feeding of the webs 15, 16 and 17 with the carbon sheets 26 and 27 around the platen, the lower reaches of the webs are entirely free of the lower clamp 72, and hence the forward movement of the carbon-paper carriage with the carriage 73 does not result in retracting any of the bight 98 over the support 47, that is, to the right at 120 Fig. 2. During such forward movement of 130

- the carbon carriage, the bight or slack at 98 is partly or wholly taken up, such bight being replaced by the next rearward travel of the lower carriage 73.
- 5 When the platen is in the Fig. 3 position, the lower clamps 72 will seize, if the typist pushes back the carbon-paper carriage at this time, with the finger-piece 57 in the Fig. 3 position. Thus a bight 98 is formed 10 every time the carbon-paper carriage 29 is pushed rearwardly, and this bight is gradually taken up by the line-spacing or other feeding of the webs around the platen. This pulling of the webs off from the spools, to 15 produce the bight or slack 98, and the subsequent pulling forward of the webs by the platen 3, do not depend upon the clamp 48, 49, 50, which may be omitted so far as these web-advancing operations are concerned.
- 20 The function of said clamp 48, 49, 50 is not to advance the web. In fact, said clamp is itself pulled along by the web. If this clamp is used, it may be aided by the clamp 25 76 in keeping the plies in register, but said clamp 76 also performs the important function of drawing the plies off from the spools, to produce the desired slack at 98, to accommodate the web to the travel of the typewriter carriage members 4, 31. It will be 30 usually found advantageous to adjust the webs at the beginning in such a way that there is an initial extra bight between 47 and 32, this bight, of course, being much greater when the carbon paper carriage carries the lower carriage 73 rearwardly than it 35 is at other times.
- There may be provided a table 99, which extends rearwardly from the support 47, and is preferably either entirely without sides, 40 except immediately adjacent to support 47, or has such low sides that the bight 98 can slip over the sides of the table. The table may be formed from two plates of sheet metal, each slideable on, and embracing a lower 45 rod 100, and having a sleeve 101 sliding on an upper rod 102, the rods 100 and 102 forming the support 47. The rear end of the plates forming the table 99 may be bent downward, as seen in Fig. 3, so that when 50 the web is drawn rearwardly by the clamp 72, it will form a bight, slack or supply which at first will lie on the table 99, but which will be gradually taken up in the line-spacing operation during the typewriting or 55 filling in of the various blanks on the web work-sheet. The plates forming the table 99 may have their edges turned up at 103 to form ears on which the sleeves 101 are mounted. These ears form edge guides for 60 the webs 15, 16 and 17, but the ears are preferably cut off close to the rod 100, so that the edge guides formed thereby are extremely short, thus allowing the webs to slip sidewise or twist on the table 99.
- 65 In order to keep the weight of the webs 15, 16 and 17, between the supports 46 and 47, from drawing the bight of the web off the table 99, thereby allowing the webs to sag down between said supports 46 and 47, the jaw 77 of each clamp 72 may be elevated above the plate 104 which forms the top of the carriage 73, and the jaws 77 may be cut off at the sides of the clamps 72 near the center, to make room for a fixed plate 105 lying between the jaws 77 and extending 70 beneath the webs 15, 16 and 17 to support them throughout their length between the supports 46 and 47. The plate 105 forms a table having an extension 106, which 75 embraces the rod 100, and a second extension 80 which embraces a rod 107, forming the lower rod of the support 46. Thus it will be seen that the webs 15, 16 and 17 are supported horizontally throughout their length from the support 46 to the support 47, except at 85 their margins which extend beyond the plate 105, and therefore can be gripped by the clamp 72. The webs do not sag between the rails 31 because the usual supporting rods shown in the patent to Jesse A. B. Smith, 90 No. 1,177,546, not seen herein, support the web where it does not rest on the carriage 28.
- On the machine herein shown, the spools 42, 43 and 44 are positioned vertically below 95 the center of the typewriting machine, and consequently below the center of the travel of the typewriter carriage. With the rolls in this position on the machine, the typist may draw the webs 15, 16 and 17 straight 100 onto the platen without any twisting whatsoever if the typewriter carriage is positioned at the center of its travel. The typist, however, will often draw on the webs with the typewriter carriage positioned elsewhere 105 than the center, thus tending possibly to some extent to twist the webs. In order to positively aline the webs at will, both as to twisting and to cause the forms printed on 110 different webs to register with each other, means may be provided whereby the typist can accurately register the webs at frequent intervals, independently of any other devices, thus avoiding the necessity of re-adjusting the other devices, especially if a 115 narrow web is used temporarily. For this purpose, the webs are shown herein as provided with perforations at identically corresponding points 108, and the end gage 18 is provided with a tapered pin 109 of the 120 same size as the perforations 108, so that the typist can draw the webs out horizontally as shown in Fig. 4, and aline and re-align the corresponding printed forms on the various plies whenever required, this being accomplished by fitting the perforations 108 over the pin 109, as shown in Fig. 4, after which the platen may be thrown back to the normal Fig. 3 position, as described 125 above. The form which has already been 130

written on, and which is just below the perforations 108 may be torn off. In many cases, as where strong webs are used, the typist may hold the webs hooked onto the pin 109, while the platen is being thrown back into its writing position, though with some webs which are easily torn it may be safer at times to merely fit the webs over the pin 109, and then allow them to spring off while the finger of the typist holds the webs against the usual smooth bar 110, to which the end gage 18 is held by the usual thumb screw 111. This bar 110 is usually grasped as a handle by the typist to throw the platen up and down, thus forming a rest for the finger of the typist in holding the webs on the pin 109.

Variations may be resorted to within the scope of the invention, and portions of the 20 improvements may be used without others.

Having thus described my invention, I claim:

1. In a typewriting machine, the combination with a traveling carriage and a revolvable platen therein, of means for feeding webs to said platen, a clamp traveling at the introductory part of the machine adapted to securely hold superposed webs together while fed to said platen, and means for releasing said clamp to permit it to be pushed rearwardly while the webs are at rest upon said platen.

2. In a typewriting machine, the combination with a traveling carriage and a revolvable platen therein, of a device movable on said carriage for holding a carbon sheet, and a clamp forming part of said device adapted to positively hold together superposed webs to prevent relative creeping 40 while traveling to the platen.

3. In a typewriting machine, the combination with a traveling carriage and a revolvable platen therein, of a device movable on said carriage for holding a carbon sheet, a clamp forming part of said device adapted to positively hold together superposed webs to prevent relative creeping while traveling to the platen, a handle extending from said carbon sheet device forwardly, to enable the 50 typist to push the device rearwardly, and a finger-piece on said handle for releasing said clamp.

4. In a typewriting machine, the combination with a traveling carriage and a revolvable platen therein, of a device movable on said carriage for holding a carbon sheet, a clamp forming part of said device adapted to positively hold together superposed webs to prevent relative creeping while traveling 60 to the platen, a handle extending from said carbon sheet device forwardly, to enable the typist to push the device rearwardly, a finger-piece on said handle for releasing said clamp, a latch for holding said clamp released, and a stop for arresting said carriage

adapted to release said latch to cause said clamp to automatically seize the webs.

5. In a front-strike typewriting machine, the combination with a traveling carriage and a revolvable platen therein, of rails forming part of said carriage, a carbon paper device running on said rails, a clamp on said device adapted to clamp webs together and including a clamp adjacent each margin of the web, a spring normally tending to make 70 said clamps effective, and a finger-piece for making them ineffective.

6. In a front-strike typewriting machine, the combination with a traveling carriage and a revolvable platen therein, of rails forming part of said carriage, a carbon paper device running on said rails, a clamp upon said device adapted to clamp webs together and including a clamp adjacent each margin of the web, a spring normally tending to 80 make said clamps effective, a finger-piece for making them ineffective, a stop embracing one of said rails for arresting said device, a latch for holding the clamps ineffective when made ineffective by said finger-piece, and connections whereby said stop releases said latch at the arrest of said carriage by said stop.

7. In a front-strike typewriting machine, the combination with a traveling carriage and a revolvable platen therein, of rails forming part of said carriage, a carbon paper device running upon said rails, a handle by which said device may be moved backward and forward, a finger-piece connected to 95 said handle, a clamp for grasping webs adapted to be controlled by said finger-piece, a spring normally making said clamp effective, a rock shaft on which said clamp is mounted, a rock shaft on which said spring is mounted, a rock arm on said clamp shaft, and a cam fast to said spring shaft adapted to rotate said clamp shaft to cause the clamp to positively seize.

8. In a front-strike typewriting machine, the combination with a traveling carriage and a revolvable platen therein, of rails forming part of said carriage, a device to which carbon sheets can be clipped running upon 100 said rails, clamps mounted on the opposite margins of said device for gripping webs to cause the webs to travel together with the carbon sheets, and means for causing said clamps to constantly tend to seize said webs.

9. In a front-strike typewriting machine, the combination with a traveling carriage and a revolvable platen therein, of rails forming part of said carriage, a device to which carbon sheets can be clipped running upon 115 said rails, clamps mounted on the opposite margins of said device for gripping webs to cause the webs to travel together with the carbon sheets, means for causing said clamps to constantly tend to seize said webs, a finger-piece for releasing said clamps, a latch 120

125

for holding said clamps released, and means for automatically releasing said latch when said device has moved its carbon sheets back to their proper position.

- 5 10. In a typewriting machine, the combination with a traveling carriage and a revoluble platen therein, of means for feeding webs to said platen, a device for enabling webs to be accurately alined, a clamp at the 10 intake portion of the machine adapted to securely hold superposed alined webs together while fed to said platen, and means for releasing said clamp to permit it to be pushed rearwardly while the webs are at rest 15 upon said platen.

11. In a typewriting machine, the combination with a traveling carriage and a revoluble platen therein, of a device movable on said carriage for holding a carbon sheet, 20 means for enabling webs to be accurately alined endwise, and a clamp forming part of said device and arranged at the intake side of the machine adapted to positively hold together superposed alined webs to prevent 25 relative creeping while traveling to the platen.

12. In a typewriting machine, the combination with a traveling carriage and a revoluble platen therein, of a device movable 30 on said carriage for holding a carbon sheet, means for enabling webs to be accurately alined endwise, a clamp forming part of said device adapted to positively hold together superposed alined webs to prevent relative 35 creeping while traveling to the platen, a handle extending from said carbon sheet device forwardly, to enable the typist to push the device rearwardly, and a finger-piece on said handle for releasing said clamp.

40 13. In a typewriting machine, the combination with a traveling carriage and a revoluble platen therein, of a device movable on said carriage for holding a carbon sheet, means for enabling webs to be accurately alined endwise, a clamp forming part of 45 said device adapted to positively hold together superposed alined webs to prevent relative creeping while traveling to the platen, a handle extending from said carriage 50 sheet device forwardly, to enable the typist to push the device rearwardly, a finger-piece on said handle for releasing said clamp, a latch for holding said clamp released, and a stop for arresting said carriage 55 adapted to release said latch to cause said clamp to automatically seize the webs.

14. In a front-strike typewriting machine, the combination with a traveling carriage and a revoluble platen therein, of rails forming 60 part of said carriage, means for enabling webs to be accurately alined endwise, a carbon paper device running on said rails, a clamp upon said device adapted to clamp alined webs together and including a clamp 65 adjacent each margin of the web, a spring

normally tending to make said clamps effective, and a finger-piece for making them ineffective.

15. In a front-strike typewriting machine, the combination with a traveling carriage 70 and a revoluble platen therein, of rails forming part of said carriage, means for enabling webs to be accurately alined endwise, a carbon paper device running on said rails, a clamp upon said device adapted to clamp 75 alined webs together and including a clamp adjacent each margin of the web, a spring normally tending to make said clamps effective, a finger-piece for making them ineffective, a stop embracing one of said rails 80 for arresting said device, a latch for holding the clamps ineffective when made ineffective by said finger-piece, and connections whereby said stop releases said latch at the arrest of said carriage by said stop. 85

16. In a front-strike typewriting machine, the combination with a traveling carriage and a revoluble platen therein, of rails forming part of said carriage, means for enabling webs to be accurately alined endwise, a carbon paper device running upon said rails, a handle by which said device may be moved backward and forward, a finger-piece connected to said handle, a clamp for grasping 90 alined webs adapted to be controlled by said finger-piece, a spring normally making said clamp effective, a rock shaft on which said clamp is mounted, a rock shaft on which said spring is mounted, a rock arm on said clamp shaft, and a cam fast to said spring 100 shaft adapted to rotate said clamp shaft to cause the clamp to positively seize. 105

17. In a front-strike typewriting machine, the combination with a traveling carriage and a revoluble platen therein, of means for enabling webs to be accurately alined endwise, rails forming part of said carriage, a device to which carbon sheets can be clipped running upon said rails, clamps mounted on the opposite margins of said device for gripping alined webs to cause the webs to travel together, and means for causing said clamps to constantly tend to seize said webs. 110

18. In a front-strike typewriting machine, the combination with a traveling carriage and a revoluble platen therein, of means for enabling webs to be accurately alined endwise, rails forming part of said carriage, a device to which carbon sheets can be clipped running upon said rails, clamps mounted on the opposite margins of said device for gripping alined webs to cause the webs to travel together, means for causing said clamps to constantly tend to seize said webs, a finger-piece for releasing said clamps, a latch for holding said clamps released, and means for automatically releasing said latch when said device has moved its carbon sheets back to their proper position. 120

19. In a front-strike typewriting machine, 130

the combination with a traveling carriage and a revoluble platen therein, of rails forming part of said carriage, a clamping device for holding webs positively together and running upon said rails, a second clamping device adapted to support webs fed to the first clamping device but allowing a free bight of webs therebetween, and means for connecting both said clamping devices so that when the first advances the webs, the webs are clamped thereto, and the other is released from the webs, and vice versa.

20. In a front-strike typewriting machine, the combination with a traveling carriage and a revoluble platen therein, of rails forming part of said carriage, a clamping device for holding webs positively together and running upon said rails, a second clamping device adapted to support webs fed to the first clamping device but allowing a free bight of webs therebetween, and means for connecting both said clamping devices so that when the first advances the webs, the webs are first clamped thereto, and the other is released from the webs, and vice versa, said second clamping device running upon fixed rails so that the typewriter carriage runs edgewise of the webs relatively thereto.

30. 21. In a typewriting machine, the combination with a traveling carriage including a revoluble platen, of a device slidable on said carriage, including a clamp to positively seize webs to cause the platen to feed said webs together, a spool support from which said webs are drawn, a second device for seizing webs adapted to draw them from the spool support while positively holding them connected to each other, and connections whereby, when one clamp is effective, the other is ineffective.

22. In a typewriting machine, the combination with a traveling carriage including a revoluble platen, of a device slidable on said carriage including a clamp to positively seize webs to cause the platen to feed said webs together, a spool support from which said webs are drawn, a second device for seizing webs adapted to draw them from the spool support while positively holding them connected to each other, connections whereby, when one clamp is effective, the other is ineffective, a finger-piece for sliding said devices, and means for accurately aligning the webs when released from a clamp.

23. In a typewriting machine, the combination with a traveling carriage and a revoluble platen therein, of a clamp sliding on said carriage for positively causing webs to feed together to said platen, a carriage supporting said clamp, rails upon which said last-named carriage runs, a finger-piece for making said clamp ineffective, a spring normally tending to make it effective, a latch adapted to hold it ineffective, and an exten-

sion of said latch adapted to strike a stop on one of said rails to release the latch.

24. In a typewriting machine, the combination with a clamp, of a rock shaft on which one jaw of said clamp is mounted, a 70 rock arm fast to said rock shaft, a second rock shaft, a segment cam on said second rock shaft, a follower on said first rock shaft engaging said segment cam, a rock arm fast on said second rock shaft, a finger-piece for 75 drawing on said rock arm to rotate its shaft to make the segment effective to open the clamp, and a latch for holding the clamp released.

25. In a typewriting machine, the combination with a clamp, of a rock shaft on which one jaw of said clamp is mounted, a 80 rock arm fast to said rock shaft, a second rock shaft, a segment cam on said second rock shaft, a follower on said first rock shaft 85 engaging said segment cam, a rock arm fast on said second rock shaft, a finger-piece for drawing on said rock arm to rotate its shaft to make the segment effective to open the clamp, a latch for holding the clamp released, an extension of said latch, and a stop for automatically releasing said latch by said extension to cause the clamp to seize.

26. In a typewriting machine, the combination with a clamp, of a rock shaft on 95 which one jaw of said clamp is mounted, a rock arm fast to said rock shaft, a second rock shaft, a segment cam on said second rock shaft, a follower on said first rock shaft engaging said segment cam, a rock arm fast 100 on said second rock shaft, a finger-piece for drawing on said rock arm to rotate its shaft to make the segment effective to open the clamp, a second clamp fast to a rock shaft of its own, another rock shaft for operating 105 said second clamp, a segment cam fast on said last-named rock shaft for operating it, a follower fast to the rock shaft of the second clamp operated by said second cam, a rock shaft comprising a spline, an arm riding in said spline for operating said shaft, a link and rock arms connecting said spline shaft and said segment shaft for causing them to turn together, a single finger-piece 110 for operating them and links extending 115 from said finger-piece to operate said clamps through their rock arm connections.

27. In a typewriting machine, the combination with a traveling carriage and a revoluble platen, of a clamp traveling on 120 said carriage adapted to compel superposed webs to feed as a unit to said platen, a spool device on which said webs are wound, a second clamp for drawing webs from the spool device and positively holding the webs 125 aligned with each other while being so drawn, and connections whereby when one clamp is effective the other is ineffective.

28. In a typewriting machine, the combination with a traveling carriage and a 130

- revoluble platen, of a clamp traveling on said carriage adapted to compel superposed webs to feed as a unit to said platen, a spool device on which said webs are wound, a second clamp for drawing webs from the spool device and positively holding the webs alined with each other while being so drawn, said spool device being fixed, connections whereby when one clamp is effective the other is ineffective, a finger-piece on said traveling clamp adapted to cause it to travel to unwind webs from said spool device to form a bight, and means for releasing the clamp which is effective at the time when the bight is formed so that the second clamp becomes effective to cause the webs to feed together.
29. In a typewriting machine, the combination with a traveling carriage and a revoluble platen therein, of a reciprocating clamp slidable on said carriage, a slide on which the clamp is mounted, a separate reciprocating clamp slidable on fixed rails, a rock shaft for operating said second clamp, a rock arm splined on said shaft for operating it, a bar fast to said slide and embracing said rock arm to cause it to travel with the carriage, a link extending from the carriage to said rock arm, a finger-piece for operating said clamps, and links connecting the first clamp and said first-named link to cause one clamp to be effective when the other is ineffective.
30. In a front-strike typewriting machine, the combination with a traveling carriage, of a swing frame in said carriage, a platen journaled in said swing frame and adapted to be swung in said swing frame so that webs can be drawn from the rear substantially straight beneath the platen, a carbon paper carrier adapted to support carbon sheets between said webs, a handle for reciprocating said carbon paper carrier upon said carriage, a clamp upon said carrier adapted to seize the margins of webs to cause them to positively feed together, and a pin on said swing frame forming a gage over which perforations in said webs may fit to positively aline the webs.
31. In a front-strike typewriting machine, the combination with a traveling carriage, of a swing frame therein, a platen journaled in said swing frame and adapted to be swung in said swing frame so that webs can be drawn from the rear substantially straight beneath the platen, a carbon paper carrier adapted to support carbon sheets between said webs, a handle for reciprocating said carbon paper carrier upon said carriage, a clamp upon said carrier adapted to seize the margins of webs to cause them to positively

feed together, means for releasing the clamp from the webs during the rearward motion of the carriage, and means for automatically causing the clamp to seize the webs at the end of the rearward motion of the carrier.

32. In a front-strike typewriting machine, the combination with a traveling carriage, of a swing frame therein, a platen journaled in said swing frame and adapted to be swung in said swing frame so that webs can be drawn from the rear substantially straight beneath the platen, a carbon paper carrier adapted to support carbon sheets between said webs, a handle for reciprocating said carbon paper carrier upon said carriage, a clamp upon said carrier adapted to seize the margins of webs to cause them to positively feed together, means for releasing the clamp from the webs during the rearward motion of the carriage, and means for automatically causing the clamp to seize the webs at the end of its rearward motion, said last-named means being adjustable to suit the varying length of forms, there being also provided means for accurately alining the webs end-wise.

33. In a front-strike typewriting machine, the combination with a traveling carriage and a revoluble platen therein, of means for swinging said platen up in said carriage to permit webs to be drawn thereunder from behind, a carbon paper holder slidable upon said carriage adapted to adjust the position of carbon paper between said webs, a clamp on each side of said holder adapted to engage the webs while being fed around the platen, a finger-piece for releasing the clamps, and alining devices for alining the webs when so released.

34. In a front-strike typewriting machine, the combination with a traveling carriage and a revoluble platen therein, of means for swinging said platen up in said carriage to permit webs to be drawn thereunder from behind, a carbon paper holder slidable upon said carriage adapted to adjust the position of carbon paper between said webs, a clamp on each side of said holder adapted to engage the webs while being fed around the platen, a finger-piece for releasing the clamps, alining devices for alining the webs when so released, a latch for holding the clamps released, and a stop adapted to arrest said holder at the rear end of its travel and simultaneously to release said latch to cause the clamps to seize the webs.
